UNITED STATES PATENT OFFICE

GEORGE A. LINLEY, OF TRUMBULL, CONNECTICUT

ROLL-HOLDER FOR RIVET SPINNING MACHINES

Application filed June 26, 1929. Serial No. 373,822.

The present invention relates to roll-holders for rivet spinning machines, and has for an object to provide a roll-holder which will effectually support the rolls in such manner that they will not separate through strain or wear, and which may be adjusted as desired to insure a proper relation of the rolls. The roll-holder is of a type in which a pair of rolls are rotatably held in a holder at a slight angle, with their concave peripheral surfaces meeting at the bottom, where they engage and form the rivet head, and separated at the top. With roll-holders heretofore in use the rolls would become separated after very little use, either due to wear or strain, with the result that a small bur would be formed at the center of the rivet head.

It is proposed in the present invention to provide a roll-holder in which the roll supporting axle may be tightened with respect to the side arms of the holder to any desired extent drawing the arms into close relation with the rolls, and in which means are provided to effectually retain the axle or pin against loosening under the severe strain to which the device is put in use.

With the above and other objects in view embodiments of the invention are shown in the accompanying drawings, and these embodiments will be hereinafter more fully described with reference thereto, and the invention will be finally pointed out in the claim.

35 In the drawings:—

Fig. 1 is a front elevation of a roll-holder, according to one embodiment of the invention.

Fig. 2 is a side elevation thereof.

40 Fig. 3 is a vertical sectional view taken along the line 3—3 of Fig. 1.

Fig. 4 is a vertical sectional view of a modified form of the invention.

Similar reference characters indicate corresponding parts throughout the several figures of the drawings.

Referring to the drawings, the roll-holder is of substantially cylindrical shape, and is provided at its upper end with the usual hexagonal flange 10, for securing the same

to the threaded shank of the spinning machine, an interiorly threaded socket 11 being provided in the upper end of the holder for this purpose. A pair of downwardly extending spaced arms or jaws 12 and 13 are provided between which the rolls rotate, the inner walls of these arms being flat and slightly inclined toward each other downwardly, so that the opening between the arms is slightly wider at the top than at the bottom. This opening is divided at the top by a downwardly projecting fin 14, the sides of which are tapered in parallel relation to the inner tapered sides of the arms, and is adapted to separate the rolls at the top, as will presently more fully appear.

The arm 13 is provided with a shouldered passage 15 while the arm 12 is provided in opposed relation with a threaded passage 16, the arm being split below this passage as at 17, and being tempered, so that a slight spring action is permitted.

The passage 16 is counter sunk at its inner end, as at 16^a, so that the plane portion of the pin will provide a full bearing surface for the rolls, as will presently more fully appear.

The rolls 18, 19 which are of the usual form, are rotatably mounted on a pin or axle 20 having a head 21 at one end and threaded at the other end, as at 22. The pin 20 is engaged through the passage 15 and screwed into the threaded passage 16, the latter passage tightly binding upon it with spring pressure so that any tendency to loosen is prevented. The pin is thus securely held in any position of adjustment and may be tightened to any desired extent to draw the arm 12 toward the arm 13, and thereby maintain a tight relation of the rolls at their point of contact. In the usual type of roll-holder the pin is shouldered adjacent the screw threads, this shoulder abutting the inner wall of the arm into which the pin is screwed, so that when it is tightly screwed into place the relation of the arms is fixed and no adjustment for wear is possible. According to my invention the screw may be tightened to any desired extent, so that regardless of wear

the rolls may be maintained in their proper tight relation. The period of use of the rolls is thus greatly extended and the formation of burs on the rivet heads and other 5 objectionable features is obviated. The pin is furthermore stronger so that the possibility of shirring-off the threaded end is prevented.

In Fig. 4 I have illustrated a modification in which the arm 13 is provided with a split 23 below the passage 16 and is also tempered, so that it supplements the binding action of the arm 12 upon the pin.

I have illustrated and described preferred 15 and satisfactory embodiments of my invention, but it will be obvious that changes may be made therein within the spirit and scope thereof, as defined in the appended claim.

Having thus described my invention, what 20 I claim and desire to secure by Letters Patent is:—

In a roll holder for rivet spinning machines, a holder body having a pair of spaced arms having upwardly diverging opposed 25 walls and capable of being drawn one toward the other, said arms having aligned pin receiving passages, one of which is threaded, the arm having said threaded passage being tempered and having a split extending 30 outwardly from said threaded passage and rendering said passage a compressible and expandible binding surface, a pair of apertured rolls disposed between said walls and having bearing contact therewith, and 35 having bearing contact with each other at the rivet spinning point outwardly of said arms, separating means disposed between said rolls adapted to maintain them in diverging relation parallel to said diverging walls, a pin having a head at one end and a threaded portion at the other end, said pin being engaged in said passages of the arms and the apertures of said rolls with the headed end abutting said arm having the 40 unthreaded passage and the threaded end engaging said threaded passage of the other arm, the threads of said threaded end extending inwardly from said threaded passage in the normal engaged relation and 45 adapted to be further screwed into said threaded passage to draw said arms one toward the other to maintain the bearing contact of said rolls with each other as they become worn, and said binding surface of 50 the threaded passage adapted to frictionally retain said pin against turning to maintain the adjusted relation of said arms and rolls.

Signed at Bridgeport, in the county of 60 Fairfield, and State of Connecticut, this 21st day of June, 1929.

GEORGE A. LINLEY.
